UNITED STATES PATENT OFFICE.

FREDRICK E. JOSS, OF BROOKLYN, NEW YORK, ASSIGNOR TO LEKTOPHONE CORPORATION, A CORPORATION OF DELAWARE.

TALKING-MACHINE.

1,318,083.

Specification of Letters Patent. Patented Oct. 7, 1919.

Application filed May 9, 1918. Serial No. 233,421.

To all whom it may concern:

Be it known that I, FREDRICK E. Joss, a citizen of the United States, residing at borough of Brooklyn, in the county of Kings, State of New York, have invented certain new and useful Improvements in Talking-Machines; and I do hereby declare the following to be a full, clear, and exact description of the invention, such as will enable others skilled in the art to which it appertains to make and use the same.

This invention relates to talking machines, and in particular to machines of the Hopkins type, in which the vibrations of the stylus, during its travel along a phonic line, are transmitted to a conical diaphragm of large area, freely supported in unconfined air, in a manner to move the entire conical portion of the diaphragm bodily.

In machines of the character specified, the diaphragm is usually attached to the rear end of a supporting bar, which is mounted to move across the record or its equivalent, and which carries a vibration transmission connection that extends from the stylus to the diaphragm; such connection preferably comprising, in addition to the stylus holder, a transmission rod or element which is received within a bore or passage extending through the bar from end to end thereof and is joined at its front end to the holder and at its rear end to the apex of the diaphragm. As usually constructed, the mounting of the stylus holder is such that the stylus will operate effectively only in connection with records of the so-called lateral-cut type, thus precluding its use with records wherein the hill-and-dale type of cutting is followed; and it is the object of the present invention, therefore, to overcome this difficulty by providing a transmission connection which shall be capable of movement from a position for playing records of one character to a position in which records of the other character can be played, and vice versa.

According to the embodiment of the invention herein disclosed, the supporting bar is mounted to turn about its axis, carrying with it the diaphragm and transmission connection; the stylus being thereafter movable relatively to the transmission rod so as to properly position it for engagement with the record. The precise details of the construction whereby this and other objects are

accomplished, as embodied in the present disclosure, are not material to the actual invention, however; and for that reason no limitation to such details is intended or to be imposed, excepting in so far as may necessarily be involved by the phraseology of the appended claims.

The accompanying drawing illustrates one form which the invention may take in practice, and therein:

Figure 1 is a side elevation, partly in section, of the improved supporting bar and associated devices;

Fig. 2 is a horizontal, longitudinal sectional view thereof, omitting the bar mounting and the turn-table;

Figs. 3, 4 and 5 are transverse vertical sections, taken respectively, on lines 3-3, 4-4, and 5-5 of Fig. 1;

Fig. 6 is an enlarged perspective view of the stylus holder and its mount;

Fig. 7 is a further enlarged detail view of one of the parts shown in Fig. 6;

Figs. 8 and 9 are fragmental perspective views of the supporting bar, showing the positions assumed by the parts when set to play lateral-and-vertical-cut records, respectively, the cap on the end of the bar being omitted;

Fig. 10 is an end view of said bar with the cap in place;

Fig. 11 is an end view of the cap itself; and

Fig. 12 is a fragmental perspective view of the supporting bar, omitting the stylus holder.

Referring more particularly to said drawing, 15 indicates generally the supporting bar of a Hopkins-type talking machine, and 16 the turn-table across which it is arranged to move, the latter element being driven from a suitable motor, (not shown), in any desired manner. The bar 15 is rotatably mounted adjacent its rear end in a sleeve 17, (Figs. 1, 2 and 3), which is itself supported by a gimbal joint 18 from a semicircular, vertical bracket 19 secured to the frame or deck of the machine, the arrangement being such, therefore, as to permit a swinging movement of the bar in both a horizontal and a vertical plane, as well as a rotary movement of said bar in either direction about its longitudinal axis.

To limit the extent of this rotary movement of the bar, so that in one position the

parts will be set for playing lateral-cut records and in the other position for playing hill-and-dale records, there is provided, according to the present construction, a ring 20, which is fixed to the bar with its inner peripheral edge in contact with one edge of the sleeve 17. The said ring and sleeve constitute companion elements, one of which is provided with two notches 21, and the other 16 with a spring-pressed pin or plunger 22 for alternative engagement in said notches, the latter having inclined bottom walls in order to push back the pin during the rotation of the bar and thereby enable it to pass from 15 one notch to the other; the end walls of the notches being made abrupt so as to terminate the rotation of the bar when the pin comes into contact therewith. The said pin is forced outward by its associated spring, 20 and by means of the pressure which it is thus enabled to exert on the wall of the notch with which it happens to be engaged, serves to hold the bar against accidental displacement. In the particular arrangement 25 illustrated, the pin is carried by the sleeve or journal 17, and the notches are formed in the ring 20; and a second fixed ring 23 is provided at the opposite side of said sleeve to hold the same in place and prevent any 30 endwise movement of the bar with respect thereto.

The transmission connection, as usual in Hopkins-type machines, consists of a stylus holder 24 and a transmission rod 25. The 35 latter is received within an eccentric bore or passage 26 formed through the bar 15, and projects beyond the same at opposite ends, the rear end of the rod being suitably fastened to the apex of the diaphragm, (not 40 shown), while its front end is connected to an extension or ear 27, formed on the base 28 of the stylus holder. The aforesaid stylus holder is resiliently connected to the front end of the bar by means of a leaf 45 spring 29, which is fastened in a two-part clamping block 30, fitted in a recess 31, provided in the bar end, said spring having its terminal projecting outwardly beyond said recess and anchored in a saw cut or slot 50 formed in the rear face of the base member 28. The recess communicates with the bore 26 of the bar, and the clamping block 30 is adjustable therein for the purpose of varying the effective length of the exposed portion 55 of the spring.

Since the transmission connection moves as a unit during the rotary movement of the supporting bar from one position to the other, it is necessary for the stylus holder 60 to be capable of a subsequent, independent movement or adjustment in order to bring it into playing position; that is, to bring the stylus into contact with the record. This independent movement, however, must be 65 of such a character as not to disturb the po-

sitions of the leaf spring 29 and the transmission rod; and for that reason, the stylus holder is preferably constructed in two separate parts or members which are rotatably connected together, the part 32 which carries the stylus being movable with relation to the relatively-fixed base member or part 28 to which the aforesaid spring and rod are fastened. Accordingly, the stylus-carrying part 32 is formed at its upper end 70 with a sleeve 33, which loosely encircles a cylindrical stem 34 that projects forwardly from the base 28, the two parts being held together by a headed screw 35. The rotating part 32 has a movement of 90° only; 75 and to determine the limits of this movement, the sleeve 33 is provided with a transverse slot 36 in which works a pin 37, set into the upper portion of the stem 34, though any other stop connection of like 80 character may be used instead of the one just described, as will be understood. The pin 37 preferably has its upper end split, as shown in Fig. 7, thereby providing a pair 85 of spring jaws 37' which are compressed in the intermediate portion 36' of the slot 36, but expand in the slightly enlarged end portions 36' thereof, thus exerting pressure against the end walls of said slot and consequently tending to retain the said rotating 90 part 32 in either of its two extreme positions. The extension 27 is preferably formed with a longitudinal slot 38, in which the end of the transmission rod is secured by means of a screw 39, such construction enabling 100 an adjustment of the rod end with respect to the holder.

The forward end of the supporting bar has fitted on it a cap or sleeve 40, which is made convex or dome-shaped at its end. 105 This portion of the cap extends beyond the bar end and provides an interior chamber 41, wherein are received the stationary base member 28 of the stylus holder, the projecting ends of the spring 29 and the rod 25, 110 and the sleeve 33, the remainder of the stylus-carrying member 32 extending outwardly through an opening 42 in the cap. The said opening, as shown in Fig. 11, is so shaped as to enable the cap to be positioned 115 on the bar after the installation in the latter of the transmission connection.

In operation, and assuming that the parts are set for playing lateral-cut records, as represented in Fig. 8, and that it is desired to play a vertical-cut record, it is necessary merely to grasp the supporting bar and turn it, (to the left, with respect to Fig. 8), until the pin or detent 22 leaves the lower notch 21 in which it was previously engaged, and enters the upper notch. During this movement, the transmission device moves as a unit with the bar, and the parts with the exception of the holder member 32, finally assume the positions illus- 125 130

trated in Fig. 9, in which the extension 27 projects upwardly, and the bore or recess 26 for the transmission rod runs along the upper portion of the bar. The stylus-carrying member 32 of the holder is then turned into Fig. 9 position to enable the stylus to engage the record, or, if preferred, the adjustment of the said member 32 may take place at the time that the bar is being rotated, both movements being effected in the latter case with one hand. The reverse movements take place when the adjustments for playing lateral-cut records is made, the parts moving from Fig. 9 position to Fig. 8 position. Further description of the operation of the invention is considered unnecessary in view of the foregoing.

I claim:

1. In a talking machine, in combination, a rotatably-mounted supporting bar; and a vibration transmission connection carried by said bar and movable with the same during the rotation thereof between a position for playing vertical-cut records and a position for playing lateral-cut records, said connection including a stylus carrier movable relatively thereto into record-engaging position.

2. In a talking machine, in combination, a rotatably-mounted supporting bar; and a vibration transmission connection carried by said bar and movable with the same between a position for playing vertical-cut records and a position for playing lateral-cut records, said connection comprising a transmission rod, and a stylus holder embodying a base member which is fixed with relation to said rod and to which said rod is attached and a stylus-carrying member connected with said base member for movement relative thereto into record-engaging position.

3. In a talking machine, in combination, a rotatably-mounted supporting bar; and a vibration transmission connection carried by said bar and movable with the same between a position for playing vertical-cut records and a position for playing lateral-cut records, said connection comprising a transmission element, and a stylus holder embodying a stylus-carrying part movable relatively to said transmission element into record-engaging position.

4. In talking machine, in combination, a rotatably-mounted supporting bar; and a vibration transmission connection carried by said bar and movable with the same between a position for playing vertical-cut records and a position for playing lateral-cut records, said connection comprising a transmission element, and a stylus holder embodying a part fixed to said transmission element and a part movable relatively to the first-named part and adapted to carry a stylus into record-engaging position.

5. In a talking machine, in combination,

a rotatably-mounted supporting bar; and a vibration transmission connection carried by said bar and movable with the same between a position for playing vertical-cut records and a position for playing lateral-cut records, said connection comprising a transmission element, and a stylus holder embodying a part fixed to said transmission element and a part rotatably related to the fixed part and adapted to carry a stylus into record 75 engaging position.

6. In a talking machine, in combination, a rotatably-mounted supporting bar; and a vibration transmission connection carried by said bar and movable with the same between a position for playing vertical-cut records and a position for playing lateral-cut records, said connection including a stylus holder having a stylus-carrying part which is initially movable with said bar and is subsequently movable relatively thereto.

7. In a talking machine, in combination, a supporting bar having a bore extending therethrough, said bar being movable between playing position for vertical-cut records and playing position for lateral-cut records; and a vibration-transmission connection disposed within said bore and movable with said bar from one of such positions to the other.

8. In a talking machine, in combination, a supporting bar having a bore extending therethrough, said bar being movable between playing position for vertical-cut records and playing position for lateral-cut records; and a vibration transmission connection disposed within said bore and movable with said bar from one of such positions to the other, said connection including a stylus carrier movable relatively thereto into record-engaging position.

9. In a talking machine, in combination, a tubular supporting bar mounted to rotate about its longitudinal axis between playing position for vertical-cut records and playing position for lateral-cut records; and a vibration transmission connection disposed within the bore of said bar and movable with the latter from one of such positions to the other.

10. In a talking machine, in combination, a tubular supporting bar mounted to rotate about its longitudinal axis between playing position for vertical-cut records and playing position for lateral-cut records; and a vibration transmission connection disposed within the bore of said bar and movable with the latter from one of such positions to the other, said connection including a stylus carrier movable relatively thereto into record-engaging position.

11. In a talking machine, in combination, a support; and a vibration transmission device carried by said support, the support and transmission device being movable as a unit 130

between playing position for vertical-cut records and playing position for lateral-cut records, said device including a stylus carrier which is lifted away from the record 5 by the movement of the support into one of such positions, and which is thereafter movable backward relatively to said support and said device into record-engaging position.

12. A stylus holder comprising a base provided with a forwardly-projecting cylindrical stem, a sleeve rotatably fitting on said stem, and a stylus-carrying part rigidly connected to said sleeve to rotate therewith into and out of position to engage the stylus 15 with a record.

13. A stylus holder for connection to a transmission rod, comprising a base, a stylus-carrying part rotatably related to said base for movement with respect thereto into and 20 out of record-engaging position, and a single resilient member anchored at one end to said base and adapted to be secured at the other end to a support for vibratably fastening the holder to the support, the rotation of the 25 stylus-carrying part being in a direction at right angles to the plane of vibration of said base.

14. A stylus holder comprising a base provided with a stem, a sleeve rotatably fitting 30 on said stem, a stylus-carrying part rigidly connected to said sleeve to rotate therewith into and out of position to engage the stylus with a record, and a pin-and-slot con-

nection between said sleeve and stem to limit the rotary movement of the sleeve in both 35 directions, the pin element of said connection having spring jaws adapted to grip the end walls of the slot so as to yieldingly hold the sleeve against displacement from either of its extreme positions.

15. A stylus holder comprising co-acting base and stylus carrying parts, one of which is rotatable with relation to the other, and a pin-and-slot connection between said parts to limit the movement of the rotatable part 45 in both directions, the pin element of said connection having spring jaws adapted to grip the end walls of the slot so as to yieldingly hold the rotating part in either of its extreme positions.

16. A stylus holder comprising co-acting base and stylus carrying parts, one of which is rotatable with relation to the other, and a pin-and-slot connection between said parts to limit the movement of the rotatable part 55 in both directions, the slot element of said connection having its ends enlarged, and the pin element having spring jaws adapted to be compressed during the passage of the pin through the central part of the slot and 60 to expand on reaching either enlarged end of the slot so as to grip the walls of said end and yieldingly hold the rotatable part in either of its extreme positions.

In testimony whereof I affix my signature. 65
FREDRICK E. JOSS.
